US00D606728S

(12) United States Design Patent
Peters

(10) Patent No.: US D606,728 S
(45) Date of Patent: * Dec. 29, 2009

(54) SKIRT

(76) Inventor: Brian Jeffery Peters, 7052 Moonlight Cir., Huntington Beach, CA (US) 92647

() Term: 14 Years

(21) Appl. No.: 29/336,838

(22) Filed: May 11, 2009

(51) LOC (9) Cl. 02-02

(52) U.S. Cl. D2/851

(58) Field of Classification Search D2/851,
D2/852, 735, 756, 779; 2/47, 71, 74, 211,
2/247
